John P. Halstead, Buffalo, N. Y.

Application June 10, 1950, Serial No. 167,323

7 Claims. (Cl. 120—32)

1

This invention relates to copy holders for manuscripts or other copy, the copy holder including means for progressively spacing the manuscript or copy to bring successive lines thereof into position for reading or copying. The device is of special convenience when used by typists or stenographers but may be used for many other purposes as convenience may dictate.

Certain copy holders of this general class have been previously proposed wherein the device may be of considerably less width than the copy and still give adequate support thereto and present the same for ready viewing or reading. In these devices the copy is supported in scroll or roll form with the outer end of the roll or scroll comprising the top of the sheet and the progressive spacing of the sheet taking place by a progressive unrolling of the copy. The present invention provides a copy holder of this general class wherein the construction is greatly simplified and improved and wherein the operation is likewise simplified and made more certain and facile.

In copy holders of this class wherein the progressive spacing is effected by a rotary unrolling movement of the copy, the rotary means for producing the spacing have previously involved conventional ratchet wheels wherein the spacing is limited to definite increments which represent multiples of the tooth pitch of the ratchet wheel. In such constructions the necessary adjustment of the copy at the beginning of a page, intermediate adjustment for accumulated variances, and other random spacing not conforming to the ratchet tooth pitch can only be effected manually and awkwardly by releasing the copy from the feeding means and adjusting it by hand.

In the present invention the rotary unrolling movement of the copy is effected by progressive rotary movement of feed roll or wheel means provided with an intermittent drive mechanism which may be gauged or indexed to produce line feeding movement to various predetermined increments which need not necessarily be multiples of a base unit and which, further, may be employed to move the copy under the direct control of the user in the same convenient manner at any increment not conforming to the gauge or index means. This is of particular importance in handling manuscript or copy which does not conform to standard typewriter spacing, either because the copy was made on non-standard typewriters or in reading from a stenographic notebook, a printed page, or a hand-written manuscript. In the latter case the line spac-

2

ing may vary from line to line, particularly when the handwriting is not on ruled pages.

The present invention provides a casing and supporting structure wherein the copy is readily arranged in roll or scroll form without necessitating the forming of sheet metal or like plates into replicas of such scroll form as has been the case in the prior art. According to the present invention there is no spirally coiled guide plate as in previous proposals, the side walls of the casing body being arranged to accomplish the winding function in a very simple manner.

In the device of the present invention the means for engaging the copy to hold it in a given adjusted position is arranged to be self-equalizing so that the copy is gripped equally at opposite sides, despite minor variations in the construction and alignment of the parts and even if the copy be folded or arranged in such a way as to be substantially thicker at one side than at the other. Further, this copy engaging means acts as a brake on the copy feed rolls which, in the form of drive illustrated herein, are otherwise free to overrun the drive means in the feeding direction. Numerous other objects and advantages of the device of the present invention will occur to those skilled in this art from a consideration of the following specification and the accompanying drawings. It is to be understood, however, that the specific form of the invention shown in the drawing and described in detail in the following description is by way of example only, and that the principles of the invention are not limited, excepting as defined in the appended claims.

In the drawings:

Fig. 1 is a longitudinal front-to-back cross-sectional view taken approximately centrally of one form of the device of the present invention;

Fig. 2 is a general top plan view thereof;

Fig. 3 is a cross-sectional view taken approximately on the line III—III of Fig. 1; and

Figs. 4, 5, and 6 are similar fragmentary elevational views, partially in cross-section, taken as indicated by the line IV—IV of Fig. 1, showing several positions of adjustment of the line space determining means.

Throughout the several figures of the drawings like characters of reference denote like parts, the numeral 10 designating a main casing part or body member which, in the present instance, comprises a single molded plastic part, but which may be otherwise fabricated, as of sheet metal or by die casting, and which need not neces-

sarily be unitary as shown, but may be built up from variously fabricated components.

The casing or body 10 includes generally side walls 11 and 12, a rear wall 13, and a combined curving top and front wall 14, the several wall portions merging smoothly to form a single continuous housing for all of the operating mechanism. The rear wall 13 curves forwardly at its upper edge and terminates in an inclined paper table formation 15 as shown in Fig. 1. The combined front and top wall 14 extends rearwardly and downwardly from its highest portion so that, in the form illustrated, it extends toward the paper table substantially perpendicularly and about mid-way of the vertical extent of the latter. These rearward and downward extensions of the wall 14 comprise bifurcations which are designated 17 and 18 in Fig. 2 and terminate short of paper table 15 a distance which is at least greater than the thickest batch of manuscript or copy which the device is to receive.

As viewed in Fig. 1, the side walls 11 and 12 are provided with concentric, generally circular openings 20 and 21, respectively. The bifurcated rearwardly and downwardly extended portions 17 and 18 terminate in generally vertical wall formations designated 22 in Fig. 1, such wall formations co-operating with the paper table formation 15 to provide in effect a V-shaped or funnel-like gap which extends downwardly and merges with the circular openings 20 and 21 of the side wall portions 11 and 12.

Referring particularly to Figs. 1 and 3, side walls 11 and 12 are provided with inwardly directed bearing formations 25 and 26, respectively, which are located beneath the forward extension of rear wall 13 and behind paper table 15. Bearings 25 and 26 give rotatable support to a feed roll designated generally 27 and supported for rotation relative to bearings 25 and 26 by means of a pair of supporting pins 28 and 29. In the illustrated instance feed roll 27 comprises a pair of telescoping sleeves 30 and 31, which include end flanges designated 32 and 33, respectively, each of which is preferably provided with a rubber or similar friction ring or tire part, designated 35 and 36, respectively, for frictional engagement with the rear face of the copy.

For holding the copy in frictional engagement with rings 35 and 36 of feed roll 27 a transverse bar 38, which, in the illustrated instance is of angular cross-section, is provided. Bar 38 has a central mounting portion 39 which lies in the bifurcation between the extensions 17 and 18 of the casing and includes a pair of lateral bearing formations or downward extensions 40 and 41.

In the illustrated instance the combined front and top wall portion 14 of the casing or body member 10 is provided with integral internal rib formations 43 and 44, which, as viewed in Fig. 1, are generally co-extensive or coincident with the circular openings 20 and 21 in the side walls 11 and 12 from the entrance to the circular openings upwardly about the peripheries of the openings to substantially their forward extremities, where the ribs terminate in portions designated 45 and 46.

The bearing formations 40 and 41 of bar 38 lie between the rear portions of ribs 43 and 44 and are pivoted thereto with play pivotal connections as shown at 48 in Fig. 1. These play connections permit rocking movement of bar 38, as indicated by the dash lines and the dot-and-dash lines in Fig. 2. A bowed leaf spring 52 is anchored

at one end to an offset extension 53 of the top and front wall formation 14 and extends rearwardly with its free end engaged in the crotch formed by angle bar 38. Spring 52 is longitudinally compressed and thus urges the bar in a counterclockwise direction about pivots 48 and thus presses the rear face of bar 38 against or toward the rings 35 and 36.

Since the spring 52 exerts its force against bar 38 centrally thereof the pressure against rings 35 and 36 is self-equalizing. The front upper surface of the central mounting portion 39 of bar 38 comprises a very convenient manipulating portion which may simply be manually depressed against the resistance of spring 52 to pivot bar 38 away from rings 35 and 36 and thus free the manuscript or copy for insertion or withdrawal. The means for rotating spool 27 to feed manuscript or copy, either at various predetermined increments or at any increment which the operator immediately desires, will now be described. In the fabrication of spool 27 by assembly of the telescoping sleeves 30 and 31 a collar 60 is assembled between the sleeve elements in such a way that it is free to rotate relative to the sleeve elements and collar 60 has a peripheral enlargement 61 which provides a chamber for receiving a clutch ball or roller 62.

The recess in enlargement 61 has an inclined face 63 and roller 62 normally rests, by gravity, in the position illustrated in Fig. 1 where it is in tangential engagement with inclined face 63 and a peripheral portion of sleeve 30. When collar 60 is rotated in a counterclockwise direction, the tendency is to clamp or wedge roller 62 between these two points of tangential engagement and thus lock collar 61 to sleeve element 30 of spool 27 for joint rotation for the full angular amount of any rotative force applied to collar 61.

On the other hand, clockwise rotation of collar 61 immediately frees roller 62 from this gripping or clamping engagement, and collar 61 rotates freely in a clockwise direction independently of sleeve 27. This provides a rotary unidirectional drive between collar 60 and spool 27 which imparts to the sleeve 27 a degree of angular rotation which is infinitely variable and directly proportional to the angular degree of rotation of collar 60. This freedom of the spool 27 to overrun the collar 60 is normally prevented by the frictional restraint imposed by the resilient pressure of bar 38 against the copy.

Referring particularly to Figs. 1 and 3, a roll feed operating lever 65 of plate-like formation is provided with bearing formations 66 and 67, and the opposite side walls 11 and 12 of casing 10 are likewise provided with bearing formations 68 and 69 to which plate 65 is pivoted as by the pivot pins 70 and 71.

An extension coil spring 73 is anchored at one end to casing 10 and at its other end to a rear lug 74 formed on lever 65 so that it urges lever 65 in a counterclockwise direction as viewed in Fig. 1, and the forward end of lever 65 comprises a manipulating portion 76 which extends through an opening 77 in the front wall 14 of casing 10 and is normally urged to the dot-and-dash line position of Fig. 1 by spring 73. The rear end of lever 65 is connected to collar 60 by means of a link 78, which is pivoted at its opposite ends to lever 65 and collar 60, respectively.

It will thus be seen that manual depression of the manipulating portion 76 to any desired degree from the dot-and-dash line position shown in Fig. 1 will impart to the collar 60 and thus to

spool 27 a degree of rotation directly proportional to the degree of depression of portion 76 of lever 65 and that release of the manipulating portion will cause it to automatically return to the dot-and-dash line position by the action of spring 76 without rotatively affecting spool 27.

Referring particularly to Figs. 1, 4, 5, and 6, a cam element 80 is fixed to a shaft 81 which is rotatively mounted in the lower front wall 14 of casing 10 and is also journaled in an auxiliary wall portion 83, which may be fixed to the lower forward extremities of ribs 43 and 44, either by being integrally molded therewith or by other means of securement. A collar designated 85 in Fig. 1 is merely a spacing collar. Manipulating portion 76 of lever 65 includes a depending lug 88 which engages the periphery of cam 80, and it will be noted that the periphery of cam 80 has three operating levels designated 90, 91, and 92, as is best shown in Fig. 6. Figs. 4, 5, and 6 show the successive operating levels of cam 80 in position to be engaged by lug 88 to gauge the paper feed means for triple, double, and single type-writer spacing, respectively.

It will be noted that when the cam 80 is set so that the surface 90 is upwardly, as in Fig. 4, the triple spacing provided for when lever 65 is depressed until lug 88 strikes the surface 90 is merely permissive and that in such position of adjustment the manipulating portion 76 of lever 65 may be depressed any desired distance within the maximum limit of the triple space setting so that any amount of rotative movement of spool 27 and consequently the degree of feeding of the copy may be effected within the predetermined maximum.

Cam 80 has a coaxial detent block 95 adjacent and fixed thereto, in the present instance by being made integrally therewith. Detent block 95 has three flat surfaces designated 96, 97, and 98, corresponding, respectively, to the cam levels 90, 91, and 92. A detent leaf spring 100 is anchored at one end to a block 101, which is rigidly fixed to rib 43. The manner in which leaf spring 100 and the flat faces of detent block 95 cooperate to retain the cam 80 in its various operating positions is believed to appear clearly from Figs. 4, 5, and 6 without further description. Shaft 81 of cam 80 extends forwardly of the casing 10, where it is provided with a manipulating knob 105 for setting cam 90.

What is claimed is:

1. In a copy holder, a paper passage and a pair of coaxial laterally spaced feed rolls mounted with peripheral portions of the rolls in said paper passage, means for yieldably holding copy against such peripheral portions of the feed rolls, said means comprising a laterally extending bar having a substantially central play connection mounting, spring means engaging against said bar substantially midway between said rolls whereby the pressure thereof is equally divided between the feed rolls, an operating member, and transmission means connecting the operating member to the feed rolls to rotate the latter.

2. In a copy holder, a paper passage and a pair of coaxial laterally spaced feed rolls mounted with peripheral portions of the rolls in said paper passage, means for yieldably holding copy against such peripheral portions of the feed rolls, said means comprising a laterally extending bar having a substantially central play connection mounting, spring means engaging against said bar substantially midway between said rolls

whereby the pressure thereof is equally divided between the feed rolls, a drive member coaxial with the feed rolls and means acting between the drive member and the feed rolls for causing the drive member and the feed rolls to rotate jointly in one direction of rotation only, an operating member, and means connecting the operating member to the drive member whereby manipulation of the operating member to and fro oscillates the drive member to advance the feed rolls directly proportionately to the degree of manipulation of the operating member.

3. In a copy holder, a paper passage and a pair of coaxial laterally spaced feed rolls mounted with peripheral portions of the rolls in said paper passage, means for yieldably holding copy against such peripheral portions of the feed rolls, said means comprising a laterally extending bar having a substantially central play connection mounting, spring means engaging against said bar substantially midway between said rolls whereby the pressure thereof is equally divided between the feed rolls, and manual drive means for the feed rolls.

4. In a copy holder, a unitary casing comprising top, side, and end walls, generally circular concentric openings in the opposite side walls of said casing, a continuous transverse opening extending entirely across the top wall of the casing and downwardly along the side walls and merging tangentially with said circular openings whereby copy moved edgewise downwardly into said transverse opening is rolled in scroll form by engagement with the edges of said generally circular side wall openings.

5. In a copy holder, a unitary casing comprising an inverted box-like structure having top, side, and end walls, generally circular concentric openings in the opposite side walls of said casing, a continuous transverse opening extending entirely across the top wall of the casing and downwardly along the side walls and merging tangentially with said circular openings whereby copy moved edgewise downwardly into said transverse opening is rolled in scroll form by engagement with the edges of said generally circular side wall openings.

6. In a copy holder, a housing comprising top, side, and end walls, generally circular concentric openings in the opposite side walls of said casing, a continuous transverse opening extending entirely across the top wall of the casing and downwardly along the side walls and merging tangentially with said circular openings whereby copy moved edgewise downwardly into said transverse opening is rolled in scroll form by engagement with the edges of said generally circular side wall openings.

7. In a copy holder, a paper passage and a pair of coaxial laterally spaced feed rolls mounted with peripheral portions of the rolls in said paper passage, means for yieldably holding copy against such peripheral portions of the feed rolls, said means comprising a laterally extending bar having a substantially central play connection mounting, spring means engaging against said bar substantially midway between said rolls whereby the pressure thereof is equally divided between the feed rolls, a drive member coaxial with the feed rolls and means acting between the drive member and the feed rolls for causing the drive member and the feed rolls to rotate jointly in one direction of rotation only, an operating member, and means connecting the operating member to the drive member whereby

manipulation of the operating member to and from oscillates the drive member to advance the feed rolls directly proportionately to the degree of manipulation of the operating member, said laterally extending bar serving to prevent the feed rolls from overrunning the drive member.
